CLAIM

The ornamental design for a stacked desk as shown and described.

DESCRIPTION

FIG. 1 is a perspective view of a stacked desk showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is the first partial enlarged view of FIG. 2 thereof;

FIG. 10 is the second partial enlarged view of FIG. 2 thereof; and,

FIG. 11 is the partial enlarged view of FIG. 5 thereof.

The dash dot dash broken lines encircling claimed subject matter shown in FIGS. 2 and 5 depict the cut lines of the enlarged views and form no part of the claim. All other broken lines depict portions of the stacked desk that form no part of the claimed design.

1 Claim, 11 Drawing Sheets
